J. Hurd.
Cloth Drying Mach.

Patented Jan 23, 1830.

1/23/1833 5142 539

Joseph Head, Junr. - Letters Patent, Dated Jan. 23, 1830.

The Schedule referred to in these Letters Patent, and making part of the same, containing a description in the words of the said Joseph Head, junr. himself of his improvement in the mode of evaporating fluids, and drying cloths, wool, silk, paper &c by means of which evaporation proceeds at all times, without assistance from the heat, called an Evaporating shaft.

To all persons to whom these presents shall come, Joseph Head Junr. of Boston, in the County of Suffolk and State of Massachusetts, gentleman sends greeting,
Be it known that the said Joseph Head, Junr. have made and applied to me, a new and useful improvement in the mode of evaporating fluids, and drying cloths, wool silk, paper &c, by means of which evaporation proceeds rapidly, at all times without assistance from heat, called an evaporating shaft.

My improvement consists in giving motion to the objects from which water or moisture is to be expelled in the manner following

Have an upright shaft, see Drawing, letters, a. a. a, with arms b. b. b. projecting from top and bottom. The upper and lower arms may be connected at their extremities by the pieces c. c. c, and also high the shaft, by pieces d. d. d. Also pieces e. e. connecting upper arms together and lower arms together. A frame will thus be formed, to which should be attached whatever is to be dried. The shaft is then to be put in motion by water or other power. The evaporation will increase in proportion to the velocity of the motion. When the motion is very rapid, the effect is not merely evaporation, but water is sensibly thrown out of the cloth by centrifugal force.

The shaft may be prepared for drying and tenting cloth in the following manner. Let there be four arms above and below connected together by c. c. c. and d. d. d. i.e. each of these arms should be double, or composed of 3 inches 3. or 4 inches apart, as in b. f. b. f. that air may pass freely between the folds of cloth, which will be tented on each side of the arms, and on the connecting pieces e. e. Four hooks, i. i. i. i. may be set all around the frame. The lower ^{more} bars may be secured to the upright pieces, c. c. d. d. and the cloth stretched as on common tent-bars. The number of arms may be increased and thus admit a greater length of cloth. The shaft may be high enough to admit several heights. Cotton cloth may be drawn around the frame in the manner of the wooden cloth, and

secured in place) at the cross pieces, & by mouth holes or rods, or some more convenient mode.

There may be frames of open work, g. g. g. attached to the shaft to receive & hold which may have not work to keep it in the place. The arrangement of the arms and frame of the shaft may be varied so as to suit the convenience of all who use it. It is useless to attempt a description of the numerous variations of which the arms are susceptible.

It may be used with great effect in evaporating salt water for the purpose of making salt. The water may be thrown into a basin, on the top of the shaft, having holes in its bottom, through which the water might pass, and trickle down ropes, boards, cloths or anything more suitable, which should be suspended and connected with the upper and lower parts of the shaft. Other liquids might also be evaporated in this way for the purpose of making sugar &c.

The shaft may be placed horizontally, or inclining to the horizon if more convenient.

This motion on a revolving shaft has an advantage over other descriptions of motions, in throwing off the vapour with some velocity, by centrifugal force.

In testimony that the above is a true specification of my said improvement as above described, I have ^{hereunto} set my hand and seal this eleventh day of January in the year of our Lord one thousand eight hundred and thirty.
